H. E. BEEDE

AIR PREHEATER

Filed Sept. 6, 1922

Invictus
Hermann E. Beede
by James C. Hamilton,
his Attorney

UNITED STATES PATENT OFFICE.

HERMAN E. BEEDE, OF ARLINGTON, MASSACHUSETTS.

AIR PREHEATER.

Application filed September 6, 1922. Serial No. 586,516.

To all whom it may concern:

Be it known that I, HERMAN E. BEEDE, a citizen of the United States, residing at Arlington, in the county of Suffolk and 5 State of Massachusetts, have invented certain new and useful Improvements in Air Preheaters, of which the following is a clear, full, and concise description.

My present invention relates to air pre- 10 heaters, and more particularly air pre-heaters to use in combination with pipeless furnaces, steam, hot water, in fact, any kind of a heating apparatus in which combustible fuel is used as, hard coal, soft coal, 15 coke and the like.

The heating apparatus which is in use universally to-day is of the old and well known type consisting of an ash pit, grate, fire box and flue, and when using coal, gases accu- 20 mulate over the fire and if not carried off or burned will result in a minor explosion. To take care of this gas, the average heater is provided with an air inlet usually through 25 the coal door over the fire box. Air enters through the openings so provided in the door and to a small extent mixes with the gases over the fire and thus allows some of the gas to burn while the greater part goes up the flue without doing any work what- 30 ever, and there is no way with this apparatus that more air can be admitted without cooling down the fire because before the air will ignite with the gases it must reach a critical temperature, and coming as it 35 does from the front of the heater, through the door, it cannot become hot to the combustible point if a sufficient amount is admitted to mix with all the gas generated from the fire.

40 In my present invention I have obviated these objections existing in the present day structures of this type, and have developed a pre-heater traveling in a reverse direction to the draft of the heater proper, entering the flue pipe in the rear of the heater, and 45 finally distributing the pre-heated air over the fire with a temperature sufficient to ignite the maximum amount of gas possible.

The principal object of my invention 50 therefore, is an air pre-heater for heaters using combustible fuel.

Another object is the saving of fuel by a more complete combustion of the gases generated from the fuel.

55 In the accompanying drawings illustrat-

ing the preferred embodiment of my invention,

Fig. 1 is a vertical central section showing the pre-heater in the proper position, and adapted to a pipeless furnace; 60

Fig. 2 is a cross section taken through the air inlet valve, and indicated by line 2--2 on Fig. 1.

Referring to the drawings, 10 indicates a pipeless furnace of the hot air type, in 65 which, 11 designates the ash pit; 12, the fire pot; 13, the space over the fire pot, and hereinafter called the combustion chamber; 14, the coal door; 15, the radiator, and 16, the flue pipe. At a point a short distance to 70 the rear of the furnace, and on the under side of the flue pipe, a perforation is made, as indicated at 17 to admit a close nipple 18, the upper end of which is fitted with a washer 19 adapted to be compressed against 75 the side of the flue pipe 16 by the screwing on of the elbow 20 against a similar washer 21 on the lower or outer side of flue pipe 16, the coupling 22' having been previously 80 engaged with the said close nipple 18 and firmly clamping coupling 21 and elbow 20 in an air tight manner on either side of the flue pipe 16. Engaged with the opposite end of coupling 22 is a perpendicular air conduit 22, the bottom end of which is adapted 85 to engage with a suitable supporting member 23. A sleeve valve 24 having valve openings 25, and 26 is adapted to loosely fit over said conduit 22, the lower end of which rests upon the upper side of the boss 27 90 formed upon the supporting member 23. Similar valve openings 28 and 29 are located directly opposite in the conduit 22, and so designed that a ninety degree turn of the 95 valve sleeve 24 will entirely close the openings 28, and 29 in the conduit 22. At ninety degrees to the conduit 22, and located on the lower inside of flue pipe 16, is another conduit 30, the rear end of which is engaged with the other ninety degree face of 100 the elbow 20. The front end of conduit 30 is adapted to receive an air tight plug 31, and to be supported by a perpendicular pin 32 securely driven into the lower side of conduit 30, and resting upon the bottom of 105 the heater radiator 33. An opening 34 is provided at the forward end of said conduit 30 and is adapted to provide for an exit at right angles to conduit 30 on either side and so positioned that the flow of air through 110

it will be in a plane parallel to the floor of said heater radiator, as shown at 33.

In operation, gases form in the combustion chamber 13, and if sufficient oxygen is present 5 ignite, but before this ignition takes place, the air containing this oxygen must be raised to a certain temperature. It is a well known fact that when air is heated or its temperature raised, it expands and weighs 10 less per cubic foot than cold air. It is commonly accepted that hot air rises of its own accord, but in reality the reverse is true as the cold air having a heavier specific gravity presses down and crowds the hot air up. 15 With this principle it will readily be seen that as the air over the fire in chamber 13 becomes heated it is elevated to the top of the dome 35 of the heater radiator. The radiator consists of an annular chamber connected 20 to the central dome 35 by means of an opening 36 located at the front of the heater. Cold air enters the valve openings 28, and 29, passes up through the conduit 22 and thence through the conduit 30 out 25 through the opening 34, around each side of the radiator, but always seeking the lowest level, and finally reaching the combustion chamber 13. In the meantime this in-flow of cold air has elevated the hot air to the 30 highest level of the radiator, and by the time the cold air arrives over the fire it has been heated to a sufficient temperature for the oxygen in it to ignite with gases formed in the combustion chamber. Regulation of the 35 amount of air coming in is controlled by the sleeve valve 24. In order for this cycle to take place it is absolutely essential that the cold air inlet be at a point below the grate of the heater. Another important result 40 is obtained with this apparatus in the added amount of heat radiated from the top of the heater radiator due to the hot air being crowded up against this surface. This principle applies in the same way to steam 45 heaters, and in fact to any heater wherein combustion of air must be utilized, and as

heat will not pass through a vacuum, air must be used in one form or another.

Having thus described my invention, what I claim as new, is:

1. In a heater in combination, a firebox, a hemispherical dome mounted on and above said firebox and provided on its upper end with an exhaust opening, an exhaust flue for consumed gases having its entrance end connected with the exhaust opening of the dome, an oxygen supply means extending longitudinally of and adjacent the lower portion of said exhaust flue, said oxygen supply means having an intake located at a point below the 55 bottom of the firebox and an exit end terminating adjacent the top of the hemispherical dome whereby oxygen is drawn from the exit end of said oxygen supply means into the hemispherical dome in a direction opposite to the direction of the normal draft of the consumed gases from the firebox.

2. An improved means for furnishing pre-heated oxygen containing fluid to the combustion chamber of a furnace comprising, in 70 combination with a furnace, a firebox, a hemispherical dome mounted on and above the firebox and provided with an exhaust passage at the top thereof, an exhaust flue surrounding the upper portion of the hemi- 75 spherical dome and having an exit end leading therefrom, a conduit comprising a right angled member having its entrance end located at a point below the bottom of the firebox of a furnace and its exit end terminat- 80 ing at a point adjacent the exhaust passage from the hemispherical dome and in the bottom of the exhaust flue whereby oxygen bearing fluid is led from the outer air to the portion of the exhaust flue surrounding the 85 hemispherical dome and there preheated and is then moved in a direction opposite to the direction of flow of the consumed gases from the fire in the firebox.

In witness whereof, I hereunto subscribe my name this 5th day of Sept., 1922.

HERMAN E. BEEDE.
